FREDERICK H. WOOD, OF CHICAGO, ILLINOIS, ASSIGNOR TO LETTIE B. WOOD, OF CHICAGO, ILLINOIS.

METHOD OF CIRCULATING AIR PAST THE HEATING SURFACES OF WARM-AIR FURNACES FOR HEATING BUILDINGS WHICH PROVIDES FRESH AIR AND VENTILATION.

Application filed February 5, 1923. Serial No. 616,913.

This invention relates to improvements in the method of circulating air past the heating surfaces of a warm air furnace, whereby fresh exterior air may be used in conjunction

5 with the recirculating air from the rooms, in such a manner that these two currents of widely differing temperature may pass, the heating surfaces of the furnace without exerting an adverse influence on each other that 10 would tend to retard their free passage to the rooms. It also provides a means of ventilating the rooms.

It has been customary to mingle the two currents, of fresh exterior air and the recirculating air from the rooms, in one common hot air chamber, or at some point prior to their passage past the heating surfaces of the furnace. Finding that this method tends to retard the desired circulation of air, I have 20 devised a method of passing these two currents past the heating surfaces in such a manner that they are entirely separated from each other and not mingled, until the fresh exterior air has been heated to a degree that will 25 cause it to expand and rise in circulation.

A volume of air must be withdrawn from the rooms to afford the entrance of an equal volume of fresh exterior air, and I accomplish this by affording a passageway for the 30 vitiated air from the rooms to the chimney flue, utilizing the draft of the chimney flue for ventilating purposes, and regulating the draft of the fire by increasing or decreasing the volume of the ventilating current.

35 Having thus described the purpose of my invention, the method of its operation is illustrated in the accompanying drawing, the nature of which will be fully understood from the description I give below when considered in connection with the drawing. The drawing is intended as an illustration and not as a limitation of my invention, the principle of which is adaptable to various forms of heating plants.

45 In the drawing Figure 1 shows the plan of a furnace in relation to the chimney flue and to a ventilating duct.

Figure 2 shows the elevation of the furnace in similar relation.

50 Figure 3 shows a modified form of the fresh exterior air compartment of the heating

chamber designed to maintain the separation of the two air currents during their entire passage through the furnace.

In Figures 1 and 2 A represents the casing or jacket of the furnace, B the heater. The air from the rooms is returned to the furnace through the return duct C, entering within the jacket through the extension J of the return duct. D is the opening in the jacket for the entrance of the fresh exterior air which passes to this point through a duct the extremity of which is open to the entrance of out of door air.

F and G are partitions extending vertically between the jacket and the heater.

These partitions form a compartment within the jacket in which the fresh exterior air is warmed by contact with the heating surfaces of the heater B. K represents one or 70 more baffles which may be interposed within the compartment to retard the circulating air or to direct its course to best advantage in warming the cold air, and may be used in any position for that purpose.

In the drawing the outlet for the heated fresh air is shown at the top of the compartment but in practice it may be desirable to locate the outlet at some other part of the compartment, the purpose of the compartment being to enable the warming of the fresh air separately and before mingling it with the recirculating air from the rooms.

L indicates openings in the jacket for warm air ducts leading to the rooms. M is the smoke pipe leading from the heater to the chimney flue N.

O is a ventilating duct extending preferably from the rooms of the building to the chimney flue and entering the flue at a point well below the point of entrance of the smoke pipe. P is a damper in the ventilating duct, to regulate the volume of air passing through it, and may be arranged to operate in unison with the front damper affording draft damper to the fire, and when the draft is open the damper in the ventilating duct closes.

Figure 3 is a modification of the fresh air compartment shown in Figures 1 and 2, in 100 that its partitions H and I extend from the bottom to the top of the jacket and have an

opening for a duct leading to the rooms, the fresh air passing through such a compartment being maintained separate from the recirculating air from the rooms in its passage through the furnace.

Having shown a means by which my method of circulating air through a furnace may be operated, I will proceed to describe the manner of its operation.

10 The fresh exterior air enters the compartment within the jacket of the furnace provided for it, and through which it passes in direct contact with the heating surfaces and is expanded and rises in circulation, having received a degree of heat quite equal to that of the recirculating current from the rooms at the point of its entrance to within the jacket of the furnace. It may then be mingled with the recirculating air current without disturbing the circulation of that current, or it may be directed from its compartment direct to the rooms without mingling with the recirculating current within the jacket of the furnace.

25 The tendency of the heated fresh air to circulate and pass to the rooms is aided by the draft of the chimney flue which draws the vitiated air from the rooms through the ventilating duct and into the chimney where it passes upward and out of doors. Naturally the air so withdrawn from the rooms must be replaced by out of door air, and the fresh air duct affords a means of least resistance to such incoming current.

35 It is obvious that the air could be withdrawn from the rooms by mechanical means, but I prefer to rely on the one at hand in the draft of the chimney flue.

40 The volume of the ventilating current may be regulated as also the volume of incoming fresh air, and the passage of the fresh air through its heating compartment may be retarded by interposed baffles or the circuitous route within the compartment.

45 The main volume of air recirculating from the rooms to the furnace through the return duct and past the heating surfaces, is expanded and circulates through the warm air ducts to the rooms, and continues that operation over and over again increasing in temperature each time until the required heat in the rooms is maintained. A certain portion of that recirculating air is continuously withdrawn for ventilation and is replaced by fresh exterior air.

55 The advantage of this method of warm air circulation is that in addition to heat it provides fresh air and ventilation to the rooms automatically without attention or by the discretion of the inhabitant.

60 I claim:—

1. A method of circulating air through a furnace which consists in maintaining a current of fresh exterior air separate from the current of recirculating air from the rooms

of the building while the current of fresh exterior air is being heated.

2. A method of circulating air through a furnace which consists in maintaining a current of fresh exterior air separate from the current of recirculating air from the rooms of the building while the current of fresh exterior air is being heated, and then mingling the two currents of air before they pass to the rooms.

75 3. A method of circulating air through a furnace which consists in maintaining a current of fresh exterior air separate from the current of recirculating air from the rooms of the building while the current of fresh exterior air is being heated, and retarding it in its passage while subjecting it to the heat.

80 4. A method of circulating air through a furnace which consists in maintaining a current of fresh exterior air separate from the current of recirculating air from the rooms of the building while the current of fresh exterior air is being heated, at the same time withdrawing a volume of air exteriorly from the rooms.

85 5. A method of circulating air through a furnace which consists in maintaining a current of fresh exterior air separate from the current of recirculating air from the rooms of the building while the current of fresh exterior air is being heated, at the same time withdrawing a volume of air exteriorly from the rooms and regulating the volume of the air so withdrawn from the rooms.

90 6. A method of circulating air through a furnace which consists in maintaining a current of fresh exterior air separate from the current of recirculating air from the rooms of the building while the current of fresh exterior air is being heated, and at the same time withdrawing a volume of air exteriorly from the rooms by means of the chimney draft.

100 7. A method of circulating air through a furnace consisting in maintaining a current of fresh exterior air separate from the current of recirculating air from the rooms of the building while the current of fresh exterior air is being heated, and retarding it in its passage while subjecting it to the heat, then mingling the two currents of air before they pass to the rooms, and at the same time withdrawing a volume of air exteriorly from the rooms and regulating the volume of the air so withdrawn from the rooms.

110 8. A method of circulating air through a furnace consisting in maintaining a current of fresh exterior air separate from the current of recirculating air from the rooms of the building while the current of fresh exterior air is being heated, and then affording it passage to the rooms without mingling it with the current of recirculating air within the furnace.

9. A method of circulating air through a furnace consisting in maintaining a current of fresh exterior air separate from the current of recirculating air from the rooms of the building while the current of fresh exterior air is being heated, and retarding it in its passage while subjecting it to the heat,

then affording it passage to the rooms without mingling it with the current of recirculating air within the furnace, and at the same time withdrawing a volume of air exteriorly from the rooms, and regulating the volume of air so withdrawn from the rooms.
